13 Claims. (Cl. 26—26)

1

This invention concerns a process and apparatus for finishing fabrics.

Various forms of apparatus are employed in finishing fabrics by applying pressure to them. The present invention is concerned with a process and apparatus for finishing fabrics by applying pressure to them intermittently by a succession of impacts as distinct from the continuous pressure used, for example, in calendering or pressing machinery.

One known way of applying pressure intermittently to fabrics by a succession of impacts, is by the operation known as beetling which is used for finishing linen fabrics and cotton goods for the purpose of closing them, without flattening the threads and also for giving a bright and ready appearance to the fabric.

This old process of beetling, is generally carried out on a machine known as a Lancashire Beetle, which has a large number of hard beechwood fallers arranged in line which are lifted by cams and allowed to fall on to a beam or roll of cloth which is situated directly beneath the row of fallers, the rate of fall being controlled at approximately 80 times per minute.

Another type of beetling machine which is used is known as the "High-Speed Spring Beetle." In this machine metallic hammers take the place of the wooden fallers of the Lancashire Beetle. These hammers are operated by an overhead cam shaft, at about 400 blows per minute giving a greater production rate than the Lancashire Beetle.

Yet another type of beetle in use incorporates a mallet type of hammer which operates between two beams or rolls of cloth.

The fabric while it is being beaten may be in multilayer form, for example it may be rolled on a beam as is customary in the usual beetling processes or on a separate roll or it may be fed beneath the beater or beaters in one or more layers.

We have found that a variety of attractive finishes can be imparted to fabrics by causing at least one beater to beat the fabric more than 600 times per minute, while the fabric is supported on a base and is being moved across the path of the beater.

Preferably there is used at least one beater which is caused to vibrate by electromagnetic means, so as to beat the fabric more than 400 times per minute. Higher frequencies are particularly suitable e. g. at least 1000 blows per minute.

Preferably the fabric is subjected to the action

2

of at least one beater which extends across the full width of the fabric.

By carrying out the beating of the fabric with a beater or beaters vibrating at a higher rate than in the customary beetling machines, e. g. at least 1000 blows per minute, advantages over the known beetling process are secured. The length of the stroke, i. e. the distance of movement of the beater towards and away from the fabric may be quite small, e. g. about one-eighth to one-sixteenth of an inch. By this method of finishing the effect required on different types of fabrics can be readily controlled which is not the case in customary methods of beetling. The operating mechanisms can, if necessary, be enclosed and isolated, also insulated, from the rest of the machine to reduce the noise.

The beater is preferably one element of an assembly which also includes a resilient means supporting said beater and electromagnetic means adapted to be intermittently energised and disposed so as to be capable of intermittently displacing said beater against the action of said resilient means. A comparatively high frequency of, for example, 1000 blows or more per minute can be readily secured by using alternating or intermittent current having a frequency of alteration or interruption of 1000 or more per minute. A customary frequency of alternating current supply is 50 cycles per second and the use of a current of this frequency enables the beater to be moved 3000 times per minute, which has been found to be a very suitable frequency to employ in carrying out the finishing of fabrics by the present invention.

The effect of supporting the beater by resilient means and causing it to vibrate in contact with the fabric more than 400 times per minute is to apply pressure to the fabric and to increase and decrease this pressure more than 400 times per minute. This pressure may be produced by a beater weighing 4 to 5 thousand pounds applied to a fabric 40 inches wide.

By the use of a beater or beaters vibrating at a high frequency of, for example, 1000 blows or more per minute it is possible to reduce substantially the weight and size of the finishing machine as compared with the known beetling machines and the electrical control makes it possible to adjust the intensity of the blows during the process. It is not necessary for the beater to be a weight which falls from any substantial height on to the fabric. It may be a weight which together with its operating mechanism rests on the fabric so that the whole assem-

ly is vibrated while sitting on the fabric. The weight may be spring-supported in a frame which carries the operating mechanism and this frame and its contents forming the whole assembly may be suspended from a resilient supporting arrangement which is adjustable in the direction of displacement of the beater to enable the pressure on the fabric to be adjusted as desired even during the vibrating operation. This enables attractive effects in varying degrees to be produced on fabrics such as brightness, closeness and a thready appearance. Moreover, by causing the beater with its operating mechanism to sit on the fabric, the amplitude of the vibration is unaffected by the position of normal repose of the beater; thus, if a seam is encountered the beater is merely raised by this to a higher position of normal repose but the vibratory beating action is unaffected.

Where the beater is electro-magnetically vibrated the intensity or force with which it strikes the fabric may be adjusted by variations in the electric current applied.

The beaters may be applied to the fabric singly or in groups according to whether the fabric is treated in a single draft or otherwise, and if desired the fabric may be passed beneath a succession of beaters.

These beaters are preferably the full width of the fabric and formed of metal but may be faced where they come in contact with the fabric i. e. on their operative faces, with non-metallic material such as wood or a yielding material such as hard rubber or plastic material.

As already stated, the fabric may be treated when wound on rollers or beams as is customary on beetling machines, but it may alternatively, be treated continuously in single or multiple layers. Moreover, it may be continuously treated while it is being passed in a single layer between a succession of rollers beneath the beating means. For this purpose a set of two or more rollers, preferably formed of or covered with yielding material such as rubber, may be arranged between a supporting roller of substantially larger diameter and the beater. The beater itself may be provided with a surface of yielding material.

The fabric when treated may be in the dry or moist state or it may even be impregnated with dyestuffs or other chemicals before treatment which then assists penetration. Heat may be applied to the fabric before or during the finishing process of the present invention.

Instead of winding the fabric on a roller or beam (which is integral with the machine) as in the customary beetling processes, it may be wound on to a separate roller by a separate winding machine and then positioned between the beater or beaters and a strong supporting roller similar to the beam of a beetle. By rotating this supporting roller, motion may be given to the roll of fabric during processing the fabric passing in single thickness beneath the beater.

If desired, there may be interposed between the beater and the fabric to be treated rubber or a rubber-like synthetic plastic or other yielding material preferably of 60° to 90° hardness (Shore). There may be used, for example, a fabric coated with rubber or rubber-like synthetic plastic. Such yielding material may, alternatively or in addition, be between the fabric and the base. The yielding material may be in sheet form so that it can be moved with the fabric. For example, the fabric may be

treated while it is confined between two surfaces of yielding material such as rubber sheets which may be in the form of endless bands or aprons of rubber covered fabric. Alternatively, the fabric may be treated in roll form, there being a multiplicity of layers of fabric with alternate layers of rubber covered fabric.

The invention includes a machine for treating fabric including beating means comprising at least one beater adapted to vibrate at a frequency exceeding 600 blows per minute, means for supporting fabric to be beaten by the beating means and means to move the fabric transversely to the direction of movement of the beater. It also includes a machine for treating fabric having at least one beater electromagnetic means to vibrate said beater at a frequency exceeding 400 blows per minute, means for supporting the fabric to be beaten and means to move the fabric transversely to the direction of movement of the beater. It also includes a machine for treating fabric having a vibrator operatively connected to the beater and means for supporting the fabric beneath said beater so that it can in turn support the weight of the beater and at least part of the weight of the vibrator.

The invention may be applied to the existing beetle machines by removing the beetle fallers and substituting for these the H. F. vibrating mechanism described.

The invention will be described further by way of example with reference to the accompanying drawings in which:

Fig. 1 is a front elevation showing one form of machine.

Fig. 2 is a corresponding sectional elevation on the line II—II of Fig. 1.

Fig. 3 is a sectional elevation of a second form of machine.

Fig. 4 is a sectional elevation of a third form of machine.

Fig. 5 is a front elevation of a fourth form of machine.

Fig. 6 is a sectional elevation on the line VI—VI of Fig. 5.

Fig. 7 is a fragmentary diagrammatic sectional elevation on the line VII—VII of Fig. 5 on a larger scale, and

Fig. 8 is a fragmentary diagrammatic sectional elevation corresponding to Fig. 7 of a modified form of the machine shown in Fig. 5.

As shown in Fig. 2, fabric 11 to be treated is carried on a beam 12 as in the customary Lancashire Beetle.

The machine includes three pairs of oven top bearings for supporting the ends of the beam in the central position as shown by the beam 12, and in side positions respectively for supporting beams being loaded with fabric for treatment and unloaded after treatment.

An electro-magnet assembly 13 is carried by pillars 14 from a frame 15 which is vertically displaceable in guides 16 at fixed side members 17 of the machine. The frame 15 has two eye-bolts 18 fixed thereto and is partially supported by way of these eye-bolts from cables 19. The upper ends of the cables 19 are connected by way of resilient tension boxes 20 (including for example a suitably disposed helical spring) to the lower ends of cables 21. Each of these cables 21 passes over a pulley 22 and its other end is fixed to a grooved wheel 23. The two wheels 23 are fixed to a spindle 24 carrying a worm wheel 25 which it engages with a worm 26 connected by way of a spindle 27 to a hand wheel 28. By rotating

the hand wheel 28 the rotation of the shaft 24 is affected thereby raising or lowering the frame 15 by movement of the cables 21 and 19.

An armature 29 is supported from leaf springs 30 having their outer ends fixed in the frame 15. This armature is rigidly connected to and integral with a centre member 31 having an insert or facing which presents a hardwood surface 32. This hardwood facing is preferably radiused at its lower surface as shown so as to beat the fabric over a relatively restricted area.

Energisation of the electromagnet assembly is controlled from a panel 33. In this machine, rotation of the beam 12 is affected through a train of gearing 34 but unlike the usual forms of beetle machine there is no need to provide for longitudinal displacement of the beam during treatment.

The whole weight of the vibrator assembly can be carried, by way of the member 31, by the fabric but any lesser proportion of the weight may be caused to be supported by the fabric by suitable rotation of the hand wheel 28. If the hand wheel is turned in a direction to lower the frame 15 the proportion of the weight is increased up to that of the full weight of the magnet assembly armature and member 31 resting upon the fabric.

If, on the other hand, the wheel is rotated so as to raise the lower ends of the cables, part or all of the weight of the vibrator is counterbalanced through the resilient connection boxes 20.

Instead of treating the fabric on a beam rotated directly by gearing the fabric may be in the form of a roll 111 (Fig. 3) wound on a roller having a spindle 112. Two levers 113 are pivoted to the machine body at 114 and at their mid portions: each of these levers has a slotted lug 113a engageable on one end portion of the spindle 112. The free end of each lever is hooked to receive a weight 115. The roll 111 rests upon a roller 116 adapted to be revolved by gearing as in the previously described form of construction.

Instead of treating the material in a batch as in the machine of Figs. 1 and 2 and Fig. 3, a continuous treatment may be effected as shown in Fig. 4 by passing fabric from a supply 211 over a rubber facing 212a on a roller 212 on to a take-up roller 214. In this construction the hardwood insert or facing 32 of the central member 31 may itself be replaced by or faced with rubber as at 213.

Another way of carrying out continuous treatment is shown in Figs. 5 to 8. As shown in Figs. 5 to 7 there is interposed between the facing 225 of the central member 31 and the rubber faced roller 212 a vertical bank of rotatable rollers 215 which are preferably rubber covered.

As shown in Fig. 8, the facing 225 of the central member 31 is dispersed with and a rubber or rubber-covered roller 223 mounted on spindle 224 is provided.

The rollers 215 are provided with spindles 216 which are freely movable in the slots of vertically slotted brackets 217 downwardly dependent from the central members 31.

The spindle 224 of roller 223 is journaled in brackets 217.

The spindles 216 and 224 are provided at one of their ends with pulleys 218 or 219. These pulleys 218 and 219 are connected by belts with a multiple grooved pulley wheel 220 on a shaft 221. The belts on the pulleys 218 are direct and those on the pulleys 219 are crossed. Shaft 221 is

driven by belt 222 from the shaft carrying roller 212. As will be seen, the fabric 11 is fed above the uppermost roller 215 and then back and forth alternately between the remaining rollers before passing round roller 212 and on to take-up roller 214. While it is passing between the uppermost of the rollers 215 and the facing 225 or the rubber roller 223, while it is passing between any pair of the rollers 215, and between the lowermost roller 215 and roller 212, while it is passing, it is subjected to the beating action effected by the vertical vibratory displacement of the member 31 acting intermittently to compress rollers 215 between the facing 225 (or roller 223) and the roller 212.

By the arrangements shown in Figures 5 to 8 the intermittent pressure or beating action between the centre member 31 of the electromagnet assembly and the roller 212 is transmitted from one to another of the rollers 215 which impact on and rebound from one another. Since the fabric is fed between the surfaces of successive pairs of rollers it is thus subjected to a plurality of high speed beatings while passing from supply roller 211 to take up roller 214. The resulting multiple treatment of the fabric accelerates the production of the effect desired and permits of a high speed of operation.

We claim:

30. 1. A machine for treating textile fabric comprising in combination an assembly consisting of a beater, resilient means supporting said beater, and electro-magnetic means adapted to be intermittently energised and disposed so as to be capable of intermittently displacing said beater against the action of said resilient means, a supporting arrangement for said assembly, means for supporting fabric beneath said beater, means to move the fabric transversely to the direction of beater displacement and means to adjust the operative position of said beater, said resilient means and said electro-magnetic means in the direction of beater displacement.
35. 2. A machine as set forth in claim 1 in which said beater is at least as wide as the fabric.
3. A machine as set forth in claim 1 in which said beater is intermittently displaced against the action of said resilient means more than 400 times per minute.
40. 4. A machine as set forth in claim 1 in which said beater is intermittently displaced against the action of said resilient means at least 600 times per minute.
5. A machine as set forth in claim 1 in which said beater is intermittently displaced against the action of said resilient means at least 1000 times per minute.
55. 6. A machine for treating textile fabric comprising in combination at least one assembly consisting of a beater, resilient means supporting said beater and electro-magnetic means adapted to be intermittently energised and disposed so as to be capable of intermittently displacing said beater against the action of said resilient means, a supporting arrangement for said assembly, means for supporting fabric beneath said beater, means to move the fabric transversely to the direction of beater displacement and means to adjust the position of said beater, said resilient means and said electro-magnetic means in the direction of beater displacement.
60. 7. A machine for treating textile fabric including an assembly consisting of a beater, resilient means supporting said beater and electro-magnetic means adapted to be intermittently en-

ergised and disposed so as to be capable of intermittently displacing said beater against the action of said resilient means more than 400 times per minute, an adjustable resilient supporting arrangement for said assembly, a roll of fabric held beneath said beater, means to move the fabric continuously transversely to the direction of said displacement and means to adjust in the direction of displacement the position of said beater, said resilient means and said electro-magnetic means.

8. A machine for treating textile fabric including an assembly consisting of a beater, resilient means supporting said beater and electro-magnetic means adapted to be intermittently energised and disposed so as to be capable of intermittently displacing said beater against the action of said resilient means, a resilient supporting arrangement for said assembly, means for supporting and continuously moving fabric transversely to the direction of displacement of the beater and means for adjusting said supporting arrangement in the direction of displacement to enable at least part of the weight of said assembly to be carried by said fabric thereby effecting a pre-loading of said resilient means.

9. A machine as set forth in claim 8 in which said beater is intermittently displaced against the action of said resilient means at least more than 400 times per second, and with a free amplitude of between about $\frac{1}{8}$ " and $\frac{1}{16}$ ".

10

10. A machine as set forth in claim 8 in which the operative face of said beater is formed of a yielding material.

11. A machine as set forth in claim 8 in which at least one side of said fabric passing in single thickness beneath said beater is in contact with a yielding material.

12. A machine as set forth in claim 8 in which said fabric is in the form of a roll formed from the fabric to be treated and a yielding material rolled up together.

13. A machine as set forth in claim 8 in which said beater is at least as wide as said fabric.
